US00D997531S

(12) **United States Design Patent** (10) **Patent No.:** **US D997,531 S**
(45) **Date of Patent:** **** Sep. 5, 2023**

(54) **BOOT**

(71) Applicant: **US Footwear Holdings LLC**,
Nelsonville, OH (US)

(72) Inventors: **Sara B. Smogowicz**, Somerville, MA
(US); **David W. LaFalam**, Foxborough,
MA (US)

(73) Assignee: **US FOOTWEAR HOLDINGS LLC**,
Nelsonville, OH (US)

(**) Term: **15 Years**

(21) Appl. No.: **29/748,665**

(22) Filed: **Aug. 31, 2020**

(51) **LOC (14) Cl.** **02-04**

(52) **U.S. Cl.**

USPC **D2/970; D2/977**

(57) **CLAIM**

The ornamental design for a boot, as shown and described.

DESCRIPTION

FIG. 1 is a front right perspective view of a boot;

FIG. 2 is a top view of the boot of FIG. 1;

FIG. 3 is a bottom view of the boot of FIG. 1;

FIG. 4 is a left side view of the boot of FIG. 1;

FIG. 5 is a right side view of the boot of FIG. 1;

FIG. 6 is a rear view of the boot of FIG. 1; and,

FIG. 7 is a front view of the boot of FIG. 1.

The broken lines throughout the drawing figures depict portions of the boot that form no part of the claimed design.

1 Claim, 7 Drawing Sheets
